UNITED STATES PATENT OFFICE.

MAGNUS H. WICKMAN, OF SPOKANE, WASHINGTON, ASSIGNOR OF ONE-FOURTH TO CARL H. CRAWFORD, OF SPOKANE, WASHINGTON.

CHILD'S CAR.

1,303,127.

Specification of Letters Patent.

Patented May 6, 1919.

Application filed December 9, 1918. Serial No. 265,937.

To all whom it may concern:

Be it known that I, MAGNUS H. WICKMAN, a citizen of the United States, residing at Spokane, in the county of Spokane and State of Washington, have invented new and useful Improvements in Children's Cars, of which the following is a specification.

This invention relates to improvements in cars, wherein propulsion is effected by the user's feet acting on the ground or running surface to impart advancing thrusts to the car, the same being essentially for children.

Children not only out-grow these cars but dealers are now required to stock numerous sizes of cars to meet the demands of the trade for children of different sizes, and when it is considered how many different types of cars are on the market, the dealer is at a decided disadvantage as regards the amount of goods of this type which it is now necessary to carry.

Therefore, it is one of the objects of this invention to provide a car which is readily adjustable from one extreme to the other to fit any size child that would be attracted to the use of such a car.

A feature of this invention is to provide a frame of scissors formation on which a suitable seat is superimposed, bearing wheels and a steering post serving to support the frame, and means to adjust the frame on the steering post to vary the height of the seat for children of different sizes.

A further feature is to so mount the seat on the frame structure that the seat will hinge on one part and slide on another part of the structure, but will at all times be held in a substantially horizontal position and in a posture to receive the user.

A further feature consists in providing a car of the tri-cycle type which will always be stable and upright, and in this connection, the invention includes a supporting frame of A-formation with the rear limb terminals supported by bearing wheels and the front apex attached to the steering post, a seat frame extending from its point of attachment with the steering post upwardly between the limbs of the supporting frame to which it is pivoted, and the seat being secured to the seat frame and slidable on the supporting frame. Thus when the supporting frame is adjusted on the steering post,

the seat is raised or lowered as the case may be.

This invention includes other features and objects which will be more fully described in connection with the accompanying drawings and which will be more particularly pointed out in and by the appended claims.

In the drawings:—

Fig. 1, is a view in side elevation of the improved child's car adjusted to the maximum height.

Fig. 2, is a plan view thereof.

Fig. 3, is a view similar to Fig. 1, with a maximum low adjustment.

Fig. 4, is a detail view showing the manner of uniting the seat frame with the supporting frame.

Fig. 5, is a detail view showing the shoulder engagement of the front of the seat with the limbs of the supporting frame.

Fig. 6, is a sectional view on line 6—6 of Fig. 5.

Like characters of references designate similar parts throughout the different figures of the drawings.

As illustrated, 1 designates a steering post which is forked at 2 to receive a bearing wheel 3, the wheel 3 being journaled on an axle 4. The post 1 is provided with foot rests in the form of trunnions 5 which serve to support the feet of the user in coasting. A plurality of adjusting holes 6 is provided for a purpose which will presently appear. Near the top of the post 1, hand grips 7 are provided to enable the user to steer the car.

A supporting frame is indicated at 8, and when the car is of the tri-cycle type as shown, the frame 8 is of A-shaped form, the terminals 9 of the limbs being preferably secured to an axle member 10. Bearing wheels 11 support the rear portion of the frame structure and the same may be journaled on the axle member 10 by screws 12. At the apex of the supporting frame is secure means, the function of which is to pivotally unite the supporting frame with the steering post in any position of adjustment selected. As shown, an eye member 13 is secured to the apex 14, and an eye member 15 is linked with the eye member 13, to form a pivotal connection. Eye member 15 has a shank 16, adapted to be extended through any one of the holes 6, in post 1, to vary the inclination

of the supporting frame 8. Means such as a cotter pin may serve to anchor the shank in its adjusted position.

A seat frame is provided which is shown 5 in the form of a bar 17, the same being relatively wide at its rear end 18 and tapering toward its front end 19. The bar 17 is interposed between the limbs of the frame 8 and is pivoted thereto at 20 so that the two 10 frames are somewhat on the order of a scissors formation. The front end 19 is provided with an eye 21 which is linked with an eye 22, fixed to the post 1, whereby the seat bar is pivotally attached to the steering 15 post 1 in a manner to freely permit steering adjustment of said post. The disposition of the frames is such that the forward end of the seat frame is the low end and the forward end of the supporting frame is the 20 high end. Thus, the rear or high end of the seat frame will always project above the low end of the supporting frame.

A seat 23 is secured at its rear end to the seat frame, such as by a hinge 24, whereby 25 the seat may have slight movement with respect to the seat frame 17. The front end of the seat 23 rests on the supporting frame 8, and this front seat end is shouldered at 25 so that the reduced portions 26, one on each 30 side, will rest on the limbs of the supporting frame while the tongue 27 projects downwardly between the limbs.

The parts are so proportioned and arranged that when the supporting frame is 35 adjusted high, the seat 23, at its forward end, will slide on the A-frame into the position shown in Fig. 1, but will always assume a substantially horizontal position, the same being true in the low adjustment shown in 40 Fig. 2. Furthermore, in any adjustment, the hand-grips 7 will always be substantially the same distance from the seat 23, because the post 1 inclines more toward the seat 23 when a lower adjustment is effected.

45 It will be seen that that portion of the frame structure comprising frames 8 and 17, are of substantially scissors formation, and that when adjustment either high or low is effected, the frame structure is equally strong, and stable.

It is believed that the advantages and utility of this invention will be clearly understood from the foregoing description, and while I have herein shown and described one form of my invention, I do not 55 wish to be limited thereto, except for such limitations as the claims may import.

I claim:—

1. In a child's car, a frame structure comprising relatively movable frames, a seat supported by said frames and movable relatively to each frame when the frames are moved, a wheeled supported steering post, wheels supporting the rear of said structure, and means adjustably connecting said struc-

ture to said post whereby said structure may be adjusted to raise or lower said seat.

2. In a child's car, a frame structure comprising relatively movable frames, wheels supporting the rear of said structure, a seat hinged to one of said frames and slidably engaging the remaining frame for supporting said seat on said frames, a wheeled supported steering post, and means adjustably connecting said structure to said post whereby said structure may be adjusted to raise or lower said seat. 75

3. In a child's car, a frame structure comprising relatively movable frames, wheels supporting the rear of said structure, a seat supported by said frames and movable relatively to each frame when the frames are adjusted, a wheeled supported steering post, one of said frames being supportingly connected with said post and the remaining frame being adjustably connected to said post whereby adjustment of said frame will raise or lower said seat. 80

4. In a child's car, a frame structure, a seat supported by said structure, wheels supporting the rear of said structure, a steering post having a supporting wheel, and mechanism pivotally and adjustably connecting said structure with said post whereby said structure may be adjusted to raise 90 or lower said seat and whereby said post may be freely turned to steer the car. 95

5. In a child's car, a wheeled steering post, seat and supporting frames both pivotally connected with said post at their front ends and one pivotal connection being adjustable on said post, a seat supported by said frames to be raised or lowered as said frames are adjusted, and a wheel for supporting the rear ends of said frames. 100

6. In a child's car, a wheeled steering post, pivotally connected seat and supporting frames connected with said post and one connection being adjustable, wheels supporting the rear of said frames, and a seat mounted on said frames and imposing an upward stress on the post by said seat frame and a downward stress on the post by said supporting frame. 110

7. In a child's car wherein propulsion is effected by engagement of the feet of the child on the running surface, a steering post having a bearing wheel, a supporting frame having a rear bearing wheel, and inclined upwardly toward the steering post, means adjustable vertically on said steering post and pivotally connected with the forward end of said supporting frame to support the same, a seat frame pivoted to said supporting frame between the ends of the former and having its forward end pivoted to said post below the point of pivotal connection of said seat frame with said supporting frame to tilt the seat frame into crossed relation with said supporting frame irre- 115

spective of the adjustment of the latter, and a seat having its rear end mounted on the rear end of said seat frame and its forward end in supported slidable engagement with 5 said supporting frame forwardly of the point of pivotal connection of said frames.

8. In a child's car, supporting and seat frames pivotally united between their ends in cross relation, a bearing wheel for the 10 lower rear end of said supporting frame, a steering post having a bearing wheel, means pivoting the lower front end of said seat frame to said steering post to permit steering movement of said post, a seat 15 mounted on the rear high end of said seat frame and having its forward end in supported slidable engagement with said supporting frame, and means pivoted to the high forward end of said supporting frame 20 and adjustable vertically on said post to elevate or lower the seat in accordance with the size of the user.

9. In a child's car, supporting and seat frames pivotally united between their ends 25 and the supporting frame having a bearing wheel, a seat mounted on said supporting and seat frames, a steering post having a bearing wheel, the forward ends of both frames being connected with said post and 30 the connection therewith of one of said frames being adjustable to relatively shift said frames with respect to each other to raise or lower said seat.

10. In a child's car, a supporting frame 35 of A-form having an axle member secured to its limbs at the base terminals thereof, bearing wheels for said axle member, a seat frame pivoted between the limbs of said supporting frame in cross relation with said 40 latter frame, a steering post having a supporting wheel, the forward ends of said supporting and said seat frames being connected with said post, a seat supported on said frames, and one of said frames being 45 adjustable on said post to elevate or lower said seat.

11. In a child's car, supporting and seat frames united in cross relation and one of 50 said frames having a bearing wheel, a steering post having a bearing wheel and being connected with said frames to support the

same, and a seat mounted on said frames, said frames being adjustable with respect to each other to raise or lower said seat.

12. In a child's car, a supporting frame 55 having bearing wheels, a steering post having a bearing wheel, a seat supporting frame carried by said post and supporting frame, and means adjustably supporting said supporting frame on said post to raise or lower 60 said seat.

13. In a child's car, a supporting frame of A-form, wheels supporting the terminals of the A-limbs, a seat bar extending between said limbs and being pivoted thereto with 65 the seat bar in cross relation to the supporting frame, a steering post supporting the front end of the supporting frame and the front end of said bar and the rear end of said bar projecting above the supporting 70 frame, a seat hinged at its rear end to the rear end of the seat bar and the front end of the seat having shouldered slidable engagement with the limbs of the supporting frame, and means for adjusting the front 75 end of the supporting frame on said post to raise or lower the seat.

14. In a child's car, supporting and seat frames united in scissors formation and including a seat for the rider, a steering post 80 for supporting said frames, bearing wheels for said post and frames, and means for adjusting said frames to raise or lower said seat.

15. In a child's car, a frame structure of 85 scissors formation having bearing wheels, a seat on said structure, a steering post supporting the forward end of said structure, and means for adjusting said structure with respect to said steering post to vary the 90 height of said structure and seat.

16. In a child's car, bearing wheels, a seat for the user, a frame supporting said seat and mounted on said wheels, a steering member, and means for adjusting said frame 95 relative to said steering member to raise or lower said seat and move said steering member toward or from said seat in accordance with the adjustment of said frame.

In testimony that I claim the foregoing 100 as my own, I hereby affix my signature.

MAGNUS H. WICKMAN.
